(57) **CLAIM**

The ornamental design for a vacuum-formed two-part vehicle capsule, as shown and described.

DESCRIPTION

FIG. 1 is a front perspective view of a vacuum-formed two-part vehicle capsule, showing our new design; FIG. 2 is a rear perspective view thereof;

FIG. 3 is an exploded front perspective view thereof;

FIG. 4 is an exploded rear perspective view thereof;

FIG. 5 is an exploded left-side elevational view thereof;

FIG. 6 is an exploded right-side elevational view thereof;

FIG. 7 is an exploded front elevational view thereof;

FIG. 8 is an exploded rear elevational view thereof;

FIG. 9 is an exploded top plan view thereof; and,

FIG. 10 is an exploded bottom plan view thereof.

The broken lines in FIGS. 1 and 2 illustrating a vehicle depict environmental matter that forms no part of the claimed design. The remaining broken lines in the figures depict portions of the vacuum-formed two-part vehicle capsule that form no part of the claimed design.
